[57] CLAIM

The ornamental design for a computer interface for infrared data transfer, as shown and described.

DESCRIPTION

FIG. 1 is a top, front and right side perspective view of an computer interface for infrared data transfer according to my design;

FIG. 2 is a top plan view thereof;

FIG. 3 is a front elevational view thereof;

FIG. 4 is a right side elevational view thereof;

FIG. 5 is a rear elevational view thereof; and,

FIG. 6 is a bottom plan view thereof.

The left side elevation of the computer interface for infrared data transfer is the mirror-image of the right side elevation as illustrated in FIG. 4.

FIG. 1

FIG. 2***FIG. 3******FIG. 4******FIG. 5******FIG. 6***
